US00D673024S

(12) **United States Design Patent**
Caffin et al.

(10) **Patent No.:** **US D673,024 S**
(45) **Date of Patent:** ** *Dec. 25, 2012

(54) **HINGE**

(75) Inventors: **Bartholomew Jeremy Caffin**, North Manly (AU); **Filip Tejszerski**, Mosman (AU)

(73) Assignee: **D & D Group Pty Ltd.**, Frenchs Forest (AU)

(*) Notice: This patent is subject to a terminal disclaimer.

(**) Term: **14 Years**

(21) Appl. No.: **29/384,885**

(22) Filed: **Feb. 4, 2011**

(51) **LOC (9) Cl.** 08-06

(52) **U.S. Cl.** **D8/323**

(58) **Field of Classification Search** D8/323, D8/327, 328, 329, 330, 336, 353; D23/303; 4/236, 240; 16/225, 250, 682, 309, 235, 16/275, 244, 379, 390, 430, 241, 238, 245, 16/236, 243, 242, 385

See application file for complete search history.

(74) *Attorney, Agent, or Firm* — Kelly & Kelley, LLP

(57) **CLAIM**

The ornamental design for a hinge, as shown and described.

DESCRIPTION

FIG. 1 is a front elevation view showing a first embodiment of our new design;

FIG. 2 is a rear elevation view showing a first embodiment of our new design;

FIG. 3 is a front view thereof;

FIG. 4 is left side view thereof;

FIG. 5 is a right side view thereof;

FIG. 6 is a rear view thereof;

FIG. 7 is a top end view thereof;

FIG. 8 is a bottom end view thereof;

FIG. 9 is a front elevation view of a second embodiment of our new design;

FIG. 10 is a rear elevation view of a second embodiment of our new design;

FIG. 11 is a front view thereof;

FIG. 12 is a left side view thereof;

FIG. 13 is a right side view thereof;

FIG. 14 is a rear view thereof;

FIG. 15 is a top end view thereof; and,

FIG. 16 is a bottom end view thereof.

The broken lines showing details in the Figures are included for the purpose of showing environmental context of the design, and form no part of the claimed design.

1 Claim, 8 Drawing Sheets
